JOINT BLENDER

Herbert T. Borgstrom, Boonton, N. J.

Application July 3, 1952, Serial No. 297,127

2 Claims. (Cl. 72—136)

This invention relates to a tool adapted to blend a cementitious joint between adjacent structural panels.

In the building industry, the use of pre-formed panels of plaster board and like material, as a substitute for a "wet wall" construction, has become more and more widespread.

When panels of the character referred to are erected, a joint of approximately one-fourth inch is left between the adjacent edges of adjacent panels, and a joint cement is applied to said joint, said cement usually being employed in conjunction with a perforated tape overlying the space between the adjacent panels.

It is customary, in the industry, to use a joint finishing blade, for the purpose of imparting a transverse convexity to the cementitious joint, throughout the length of the joint. Thereafter, when the joint hardens, it is sanded down and on completion of the work, the joint is rendered substantially invisible.

When a conventional blade is used, it is commonly drawn transversely of the joint, and as a result, ridges are left throughout the length of the joint, which are difficult to sand down.

It is, accordingly, the main object of the present invention to provide a joint blender which is so formed as to have means embodied therein adapted not only for retaining the blade in a normally flat condition, but also adapted for bowing the blade transversely whenever desired, thus to impart a curvature to the joint finishing edge of the blade, which curvature will be transmitted to the cementitious joint throughout the length of said joint.

Another important object is to provide a tool of the character referred to wherein the means employed for bowing the blade transversely will be brought into operative relation to the blade portion of the tool merely by exertion of pressure, in the direction of the cementitious joint, against the handle of the tool.

Yet another object of importance is to provide a tool as described wherein the above stated, desirable results will be obtained, while at the same time permitting the tool to be manufactured at a nominal cost, thus to bring it within the reach of the ordinary home owner, who uses a tool of the type stated only at comparatively rare intervals.

Still another object is to provide a tool as stated, wherein the means embodied therein for bowing the blade transversely will be so designed as to act efficiently when brought into use, even though the tool may be in the hands of a comparatively unskilled worker.

Other objects will appear from the following description, the claims appended thereto, and from the annexed drawing, in which like reference characters designate like parts throughout the several views, and wherein:

Figure 1 is a top plan view of a tool formed in accordance with the present invention, a pair of adjacent structural panels, and a cementitious joint bonding adjacent edges of said panels, being illustrated fragmentarily;

Figure 2 is a side elevational view of the tool as it

2

appears when it is in use, the dotted lines illustrating the normal position of the parts, in which the blade of the tool is flat, and the full lines illustrating a position of the parts effective to bow the blade transversely, the building wall to which the tool is applied being illustrated in vertical section;

Figure 3 is a transverse sectional view taken on line 3—3 of Figure 1; and

Figure 4 is a perspective view of the tool per se.

Referring to the drawings in detail, the reference numeral 10 has been applied to a pair of side-by-side structural panels, adjacent edges of which are spaced apart as at 12. Cementitious material 14 is applied to said panels, said material being coated upon the adjacent edge portions of the panels and filling the space 12 between said adjacent edge portions. It will be understood, in this connection, that if desired, a perforated building tape can be used with the joint cement 14, the tool constituting the present invention being so designed as to be capable of efficient use whether or not a tape of this type is employed.

In using a cement 14, it is the customary practice to first plaster said cement on in a substantially flat condition, after which the cement is given a transverse convexity, so as to feather out the opposite longitudinal edges of the cementitious joint.

In this connection, the tool which I have designed is so formed as to be usable first, for plastering on the cement in a substantially flat condition, and second, for imparting the desired transverse convexity to the cement.

The tool, in this regard, includes a handle member designated generally by the reference numeral 16, and a blade carried by said handle member and designated generally by the reference numeral 18. These will be described in turn.

Considering first the construction of the handle member 16, said handle member includes an elongated handle 20 which can be formed of wood, plastic, or other material and having a pressure arm 26 at one end and a spring portion or shank 22 at the opposite end, said handle having rounded ends in the illustrated embodiment of the invention and affording a grip for a user.

Embedded in the handle 20 is a spring shank 22. The spring shank 22 is of arcuate formation, as readily seen from either Figure 2 or Figure 4, said shank being curved longitudinally so as to dispose the other end of the shank under and in spaced relation to the handle 20.

Said other end of the shank is flattened as at 24, and rivets or other fastening elements are employed for securing the flattened end 24 to the apex end of the blade 18.

To the other end of the handle 20 there is fixedly secured one end of a pressure arm 26, said arm being relatively short and relatively curved longitudinally. It may be noted, in this connection, that the pressure arm 26, the handle 20, and the spring shank 22 are all aligned longitudinally, as best shown in Figure 1.

The pressure arm 26 extends downwardly from the handle 20, in the direction of the broad end of the blade 18, and secured fixedly to that end of the pressure arm 60 remote from the handle 20 is the intermediate portion of a cross head 28 carried by the pressure arm. The cross head 28 is disposed transversely of the body and of the blade 18, and is extended in parallelism with the plane of the normally flat blade 18.

The cross head 28 is of inverted U-shaped formation, and is integrally formed, at its opposite ends, with depending fingers 30, said fingers being normally spaced from the blade 18 as shown by the dotted line position of the fingers in Figure 2.

The blade itself is fashioned from a single piece of flat material capable of being springably flexed trans-

versely, and metal, plastic, or any other material having the desired springable characteristics can be employed. In this connection, the blade 18 is of approximately triangular shape, having side edges 32 converging toward one end of the blade to point the blade at said one end. The pointed end of the blade is secured fixedly to the flattened end 24 of the spring shank 22.

At the other end of the blade 18, there is provided a straight joint finishing edge 34, said edge being disposed transversely of the blade and body, in parallelism with the bight of the cross head 28.

In use, the blade 18 will normally be flat, as shown in Figure 4, and in this position of the parts, the tool is employed for coating the joint cement 14 upon the panels 10 in such a manner as to apply a flat coat of cement to said panels.

Subsequently, when it is desired to convex the joint transversely thereof, the user need merely exert a pressure upon the handle 20, in the direction of the joint, as a result of which the pressure arm 26, and the cross head 28, will be shifted to the full line position thereof shown in Figure 2, against the spring action of the shank 22. As a result, the fingers 30 will be caused to engage the opposite side edge portions of the blade 18, adjacent the joint finishing edge, and the result will be that the blade 18 will be curved transversely, as shown in Figure 3.

The blade 18 is aided in its springable flexure to a transversely curved condition by the joint cement itself, said cement resisting movement of the blade toward the space 12, along the longitudinal center line of the blade, but offering no resistance to movement of the side edges of the blade against the panels 10, since the cement is free to flow outwardly or inwardly from said side edge portions of the blade when the side edge portions are forced toward the panels.

It is believed apparent that the invention is not necessarily confined to the specific use or uses thereof de-

scribed above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A trowel comprising a substantially triangular flexible blade having two equal converging sides, a substantially acute handle member having a pressure arm at one end and a spring portion at the opposite end secured to the apex of said converging sides, a handle on said handle member, a crosshead on the end of said pressure arm, and a depending finger affixed to each end of the crosshead and normally spaced from the blade whereby pressure on said handle will bring the pressure fingers into contact with the side edges of the blade to flex the blade on a longitudinal axis around a mortar joint.

2. A trowel comprising a flexible blade, a handle member centrally disposed above said blade and secured thereto at one of its ends, a crosshead at the other end of said handle member, and a pressure member extending from each end of said crosshead for contact with opposite outer edge portions of said blade, said pressure members being unsecured to the said blade whereby pressure on said handle member will tend to bow said blade about a mortar joint.
